UNITED STATES PATENT OFFICE.

JOHANNES MARTINUS VAN HAASTEREN, OF SCHIEDAM, NETHERLANDS, ASSIGNOR TO
NAAMLOOZE VENNOOTSCHAP: "DE KOMEET," OF SCHIEDAM, NETHERLANDS, A
CORPORATION OF THE NETHERLANDS.

CAN-BODY-FORMING MACHINE.

Application filed January 26, 1927, Serial No. 163,772, and in the Netherlands February 11, 1925.

The invention relates to can body forming machines and particularly to that part of these machines in which the blanks, provided with bent edges, are wrapped around an expansion horn by means of outside forming flaps and the edges interlocked, whereafter a compressing hammer, when rising, presses the interlocked edges of the blank clasped one in the other, against the horn and completes the formation of the seam.

With the known machines of this kind it has been found difficult to make cans of various diameters upon one and the same horn. If cans having, for example, a diameter 15 mm. larger than others are to be made, one has to make use of another horn and other forming flaps. The expansion of the known horns is obtained by causing sidepieces of the horn to swing around axes parallel to the 20 axis of the horn itself. A great part of the periphery of the sidepieces therefore does not partake of the increases of the diameter of the horn. Moreover the mechanism for moving the sidepieces does not allow a displacement to such an extent as would be required to obtain the desired larger diameter.

The chief object of the invention is to overcome this difficulty and to obtain a machine in which, with one horn and one set of forming flaps, can bodies can be made of various sizes.

To this end, according to the invention, the sidepieces of the expansion horn are 35 made movable laterally parallel to each other, about perpendicularly to the axis of the horn. A small displacement of the sidepieces is then sufficient to obtain the expansion necessary to stretch the blank around 40 the horns, so that cans varying in diameter e. g. from 78 mm. up to 82 mm. may be made with one horn.

The mechanism imparting the up and down movement to the compressing hammer 45 may be used to engage simultaneously the sidepieces of the horn.

In constructing this mechanism one is free to choose the moment at which the hammer presses the seam in dependence of the expansion of the horn.

According to the invention now the arrangement is made in such a way that first

the expansion of the horn is reaching its maximum value. Thereafter the hammer still rises, but the expansion of the horn is 55 decreasing already slightly and in the moment that the seam is being pressed, the body lies free around the horn.

This may be considered to be an important advantage over the known constructions, 60 in which the expansion of the horn is still increasing while the bent edges of the body-blank are already pinched under the hammer, and the expansion only ends when the hammer has reached its highest point.

The invention and its features will be more fully understood from the claims and with reference to the accompanying drawings in which a device according to the invention is illustrated by way of example.

Fig. 1 is a rear elevation of the horn with flaps and hammer.

Fig. 2 is a side elevation thereof.

Fig. 3 is a diagram showing the highest position of the hammer.

Fig. 4 is a horizontal section of the horn.

Fig. 5 is a side elevation of one of the wedges.

Fig. 6 is a rear elevation and

Fig. 7 a side elevation of the central portion of the horn.

The expansion horn comprises a central portion 1 and two side pieces 2 and 3. The central portion is attached to the portion of the machine by the flange 4. At the rear 85 side the supporting bolt 5, carrying the horn 6, is secured in the central portion.

The movable side pieces 2 and 3 are guided with respect to the central portion by the set pin 7 and are pulled towards their innermost position by the spring 8.

Between the side piece 2 and the central portion the wedge 9 is located, between the side piece 3 and the central portion the wedge 10. The said wedges are provided at one side with an inclined portion 11, sliding along the pieces 12, and at the other side with an inclined portion 13. They project outside the side pieces and are there provided with hardened steel pressure pieces 14. The 100 wedges are provided with longitudinal slots 15, through which project the spring 8 and the set pin 7.

The wedges 9 and 10 may be driven in

axial direction (Figs. 1 and 2) by means of the bell crank levers 16 adapted to swing about a pin 17. The said levers are actuated by the sliding piece 18 provided at the upper side with a pushing block 19 and guided in a side piece 20 secured to the hammer block 21. The sliding piece 18 is surrounded at the lower end by a helical spring 22, mounted in such a manner, that it tends to force the sliding piece downwardly, which latter may be forced upwardly against the spring action by the bolt 23, mounted in a pressure plate 24.

The hammer 21 is moved up and down in a supporting piece 25 in a guide way (not shown) by means of the driving rod 26, the lower end of which is rotated by means of a crank schematically indicated by 27. The upper head of the driving rod 26 is made integral with pressure plate 24. It embraces the pin 28, constituting a part of the supporting piece 25 of the hammer. Between the head of the driving rod and the pin 28 an eccentric adjusting sleeve 29 is arranged. This sleeve may be turned into different positions and may be clamped in the head by means of the clamping bolt 30.

The hammer 21 is provided at the upper side with a hitting strip 31, by means of which the seam may be pressed against a strip 32 in the lower side of the horn.

At the upper side of the horn the strip 33 is arranged, over which strip the plate to be bent is bent. Above the horn the flap-holder 34 is located which at the lower end opposite the strip 33 is provided with a strip 35.

The flaps 36 and 37 are rotatable about the pins 38 in the flap-holder 34. The flaps are connected at the points 39 to rods 40 by means of which they may be moved up and down.

At the lower end the flaps are provided with adjustable angular pieces 41, supporting the steel plates 42. The adjustment of the angular pieces 41 is effected by means of the bolts 43 in oval holes 44.

The operation of the device is as follows:

Around the expansion horn 1, 2, 3 the body plate already provided with cut-off corners and bent edges is bent by means of the flaps 36 and 37, so that the bent edges interlock. This interlocking of the edges is effected just prior to the forming flaps having reached their narrowest position. At this moment the hitting block 19 contacts with the bell crank levers 16, whereby the wedges 9 and 10 are pressed and the side pieces 2 and 3 of the horn are forced outwardly, so that the blank with interlocked side edges is stretched tightly around the horn.

When the expansion horn starts expanding the hammer 21, which is already ascending is located at a distance of about 8 mm.

from its uppermost position. In the period of stretching the blank the strip 31 of the hammer is located at a distance of about 2 mm. from the strip 32 in the horn and these strips may approach each other entirely for the reason that the flaps 36 and 37 have already been moved away from each other. At the same time the expansion of the horn is already decreasing which may appear from a comparison of Figures 2 and 3. Finally the hammer presses the edges of the blank into a permanent seam.

In Fig. 2 the position is shown, in which the pressure plate 24 occupies its highest position, i. e. in which the side pieces 2 and 3 are farthest apart.

Now if the crank 27 moves on in the direction of the arrow, then the plate 24 is lowered while the block 21 ascends still further.

In Fig. 3 the highest position of the pin 28 is denoted by 28'. The hammer block then forces together the bent edges of the body plate. In this position the plate 24 is already lowered to 24', i. e. the side pieces in the expansion horn have already been pulled inwardly by the spring 8.

In order to explain the advantage of this construction the following is remarked.

Assuming that cans are to be made, having a diameter of 60-116 mm. increasing in succession with 2 mm., consequently 28 different diameters, then with this system there are required: 1 expansion-horn of 60-63 mm., 1 do. of 63-66, 1 do. of 66-69, 1 do. of 69-73, 1 do. of 73-78, 1 do. of 78-82, 1 do. of 82-87, 1 do. of 87-92, 1 do. of 92-98, 1 do. of 98-106 and 1 do. of 106-116 mm., making totally 11 expansion horns with one set of forming flaps adapted for all types.

In other constructions 28 expansion horns with 28 forming flaps are required for the same purpose. Moreover the construction of the novel horns is much simpler and much cheaper than the known ones.

I claim:

1. In a can body forming machine, an expansion horn comprising two sidepieces laterally movable parallel to each other for expanding the horn, means for wrapping a blank around said sidepieces and interlocking the edges thereof, a hammer adapted to compress the interlocked edges against the horn to form them into a seam, and mechanism adapted to actuate said hammer and to simultaneously force said sidepieces apart.

2. In a machine for forming can bodies from blanks, a substantially cylindrical expansion horn comprising a relatively fixed central member, two sidepieces movable toward and away from each other for expanding the horn, resilient means drawing said sidepieces toward each other, longitudinally movable wedge members between said central member and said sidepieces adapted to

force said sidepieces radially away from each other, and a hammer adapted to press the edges of the blank into a seam.

25

3. In a machine for forming can bodies from blanks, and expansion horn comprising sidepieces movable relative to each other, expanding means for positively moving said sidepieces away from each other, a hammer adapted to press the edges of the blank into a seam, and mechanism adapted to simultaneously actuate said hammer and said expanding means.

30

4. In a machine for forming can bodies from blanks, an expansion horn comprising sidepieces movable relatively to each other, expansion means for positively moving said sidepieces away from each other, a hammer adapted to press the edges of the blank into a seam, and mechanism adapted to simultaneously actuate said hammer and said expanding means, said mechanism comprising a pitman rod pivoted to said hammer, and

35

40

an arm fixed to said pitman rod, extending transversely thereof, and operatively connected to said expanding means.

5. In a machine for forming can bodies from blanks, an expansion horn comprising sidepieces movable relative to each other, expansion means for positively moving said sidepieces away from each other, a hammer adapted to press the edges of the blank into a seam, and mechanism adapted to simultaneously actuate said hammer and said expanding means, said mechanism comprising a pivot pin on said hammer, a pitman rod having one of its ends pivotally mounted on said pin, and eccentric adjustment sleeve interposed between said pin and said rod, and a transverse arm fixed to said pitman rod and operatively connected to said expanding means.

In testimony whereof I affix my signature.

JOHANNES MARTINUS van HAASTEREN.
